UNITED STATES PATENT OFFICE.

SILAS N. CHANEY, OF GRANGEVILLE, LOUISIANA.

HAIR-CLIPPER.

SPECIFICATION forming part of Letters Patent No. 512,009, dated January 2, 1894.

Application filed September 22, 1893. Serial No. 486,152. (No model.)

To all whom it may concern:

Be it known that I, SILAS N. CHANEY, of Grangeville, in the parish of St. Helena and State of Louisiana, have invented new and Improved Hair-Clippers, of which the following is a full, clear, and exact description.

My invention relates to improvements in devices for clipping hair, and the object of my invention is to produce a very simple and inexpensive device which may be easily manipulated, which is adapted to cut hair very smoothly and evenly, and which is constructed and arranged in such a way that the severed hair is carried away, so that the operation is extremely neat. The hair is carried away by an air current as hereinafter described, and this same current also serves to carry off any loose dandruff, &c., in the hair.

To these ends my invention consists of certain features of construction and combinations of parts, which will be hereinafter described and claimed.

Reference is to be had to the accompanying drawings forming a part of this specification, in which similar figures of reference indicate corresponding parts in all the views.

Figure 1 is a longitudinal section of the hair clipper embodying my invention. Fig. 2 is a broken plan view of the same, with the body thrown open. Fig. 3 is a cross section on the line 3—3 in Fig. 1. Fig. 4 is a detail sectional view illustrating the relative positions of the slotted disk and the revoluble knife which turns thereon; and Fig. 5 is a similar detail, showing the knife in another position.

The machine is provided with a tapering tubular body 10, which is attached at its upper edge as shown at 11, to a collar 12, this being attached to one end of the hose 13, and the latter is adapted to connect with an exhaust fan so that a current of air may be drawn through the body 10, this current serving to operate the knife and remove the cut hair as herein-after described. The body 10 is held closed against the collar 12 by a spring catch 14 which may be of any suitable kind, and by releasing the catch and throwing open the body as shown in Fig. 2, the inner mechanism may be reached and easily adjusted. The body of the clipper is provided with a suitable handle 15, by which it may be easily

manipulated, and the outer or reduced end of the body is closed by a plate 16 which is provided with radial slots 17, these having cutting edges 18 on their inner sides, as shown clearly in Fig. 5.

A revoluble knife 19, turns flatwise on the inner side of the plate 16, this knife having cutting edges 20, which as they slide over the edges 18, cut the hair which projects inward through the slots 17. This construction provides for a shear cut, so that the hair is cut smoothly and without pulling. The knife 19 is secured to the lower or outer end of a shaft 21, which extends longitudinally through the body 10, and turns in suitable bearings as described below, this shaft having at its outer end a square tenon 22, which fits in a mortise in the center of the knife, and the end of the shaft is threaded to receive a nut 23 by which the knife is fastened in place, and the knife is recessed as shown at 24, so as to receive the nut and permit the knife to turn flat against the plate 16. Any suitable means may be employed for fastening the knife to the shaft, without affecting the principle of my invention.

The shaft 21 turns in cross pieces 25 and 26, which are secured to the body 10, and the inner or upper cross piece 26 has threaded in it a set screw 27, which is seated in one end of the shaft 21, and by means of this set screw the shaft may be moved longitudinally so as to hold the knife 19 snugly against the slotted plate 16. On the shaft 21 is a propeller or wind-wheel 28, which may be of any suitable construction, and which is held to the shaft by means of a set screw 28^a. The pitch of the propeller or wind-wheel blades is such that the wheel is turned by a current of air passing inwardly through the body 10.

A brake 29, composed of spring metal, is secured at one end as shown at 30, to the inner side of the body 10, and at a point opposite the propeller, the spring of the metal being such as to normally hold the brake out of contact with the wheel. The brake is provided with a shank or push button 31 which extends outward through a slot in the wall of the body 10, and by pushing inwardly on the button the brake may be moved into the path of the propeller blades so as to prevent the wheel and knife from turning, but it will be

observed that this does not interfere with the draft of the machine, and the air current acts while the wheel is not in motion, to carry off the hair in the machine or any loose material 5 on the head that is being operated on. On the shank 31 is a catch or shoulder 32, which is adapted to engage the body 10, so as to hold the brake in a position to stop the wheel.

The machine is operated by starting the 10 exhaust fan so as to create a draft through the hose 13 and body 10, after which the body is moved over the hair to be cut, with the slotted plate 16 next the hair. The air draft causes the hair to be drawn through the slots 15 17, and the revolving knife cuts it, while the air draft carries the hair away.

It will be understood that the hose 13 and the fan which causes the draft, may be arranged in any convenient place, so that the 20 hair may be deposited in such a manner as to leave the person of the operator, the one operated on, and the room in which the operation takes place, entirely free from loose hair, dandruff, &c. This is because the draft generated in the machine is sufficient to draw in, 25 through the slotted plate 16, all the loose hair, dandruff, &c., on the head of the person operated upon and expel the same through the hose 13, so that there is no chance for the 30 said loose materials to fly over the person and about the room.

Having thus described my invention, I claim as new and desire to secure by Letters Patent—

35 1. A hair clipper, comprising a hollow body having a slotted plate at one end, a revoluble knife arranged to turn on the inner face of the slotted plate, and a hose connected to one 40 end of the body and adapted to connect with an exhaust fan, substantially as specified.

2. A hair clipper, comprising a hollow body having a slotted plate at one end and a hose at the other, a revoluble propeller or wind-wheel mounted in the body, and a knife driven by the propeller and turning on the inner 45 face of the slotted plate, substantially as specified.

3. A hair clipper, comprising a hollow body having a slotted plate at one end and a hose at the other, a longitudinally adjustable shaft 50 mounted in the body, a knife carried at one end of the shaft and turning on the inner face of the slotted plate, and a wind-wheel or propeller to drive the shaft, substantially as specified. 55

4. A hair clipper, comprising a hollow body having a slotted plate at one end, a revoluble knife turning on the inner face of the slotted plate, a propeller to drive the knife, and a 60 brake for the propeller, substantially as specified. 60

5. A hair clipper, comprising a hollow body having a slotted plate at one end, cross pieces mounted in the body, a revoluble shaft longitudinally adjustable in the cross pieces, a 65 knife on the shaft, turning on the inner face of the slotted plate, a propeller or wind-wheel on the shaft, and a hose connected with the body and adapted to connect with an exhaust fan, substantially as specified. 70

6. The combination of the hollow body, the slotted end plate, the revoluble knife, the revoluble propeller to drive the knife, the brake to engage the propeller, and a catch to hold the brake in locked position, substantially as specified. 75
